COKE OVEN DOOR LATCH

Paul Van Ackeren and Franz Doll, Essen, Germany, assignors, by mesne assignments, to Koppers Company, Inc., Pittsburgh, Pa., a corporation of Delaware

Application November 29, 1951, Serial No. 258,792

7 Claims. (Cl. 292—259)

The present invention relates to a door locking device for horizontal coke ovens, wherein the door member when in locked position is kept close to the door frame by spring pressure on a latch bar carried by a bolt and wherein a bolt carrying a latch bar is situated outside the pressure-way between the lock spring and latch bar when the door locking device is in the locked position, and the lock is loosened by the latch bolt so that it acts on the lock spring and interrupts the spring pressure on the latch bar.

The main object of the present invention consists in providing the door lock with such a construction that it may be used either for latching by means of lock spring pressure or for latching without spring pressure, and by tightening by means of bearing screws provided on the bolt. The necessity of latching coke oven doors provided with lock springs but without applying the spring pressure, will arise for instance from the failure of operation of the individual spring washers in a united assembly when no spares are at hand and the supply of spare springs will require much time. It may also happen that the mechanical device for operating the bolt to compress the springs fails, and the repair thereto is somewhat delayed so that a manual latching is necessary without employing the spring pressure. The present invention effects this manual unlatching only by the application of a pressing effect of the bolt on a hub on the latch bar, which pressing effect is induced by turning a screw threaded bolt on mating screw threads. This action requires less power when loosening the door lock than is required for compression of the springs when all the spring washers are operative for locking action.

A more specific object and advantage of the invention is the ready attainment of the main object by easily operable means in the simple form of a latch bar hub with a collar and a latch bolt with a collar which coact to compress the spring, and in which the latch bar and hub are reversible, whereby the door may be latched by the same latch bolt and latch bar without use of the spring, and more particularly by merely rotating the latch bolt in a screw threaded bearing therefor on the door as in the prior conventional method of manual latching of coke oven doors.

A further specific object and advantage of the invention is the provision of screw threads for swinging of the latch relative to a hub for supporting it on the latch bolt whereby the hub may be threadedly adjusted in an axial direction of the bolt without a corresponding turning of the entire latch bar for the purpose of adjusting the sealing pressure.

A still further object and advantage of the invention is the provision of a threaded construction between the hub and the rest of the latch bar whereby on rotation of the rest of the latch bar on the hub, the hub is restrained from turning whereas the rest of the latch bar, in moving to unlatching relation, automatically moves out away from the door, thus permitting the use of arms for the latch bar in close proximity to oven parts in the area of the doorway which may be moved out of contact therewith, without

2

requiring other great power to be applied for the purpose should the sealing spring be compressed too much thus jamming the arms against such oven parts, in unlatching the door.

5 In the accompanying drawings forming a part of this specification and showing for purposes of exemplification a preferred apparatus and method in which the invention may be embodied and practised but without limiting the claimed invention specifically to such illustrative instance or instances, the drawings show a horizontal section taken through a coke oven door embodying the features of the present invention, said door being in operating position at the end of a coking-chamber of a horizontal coke oven and wherein the door is shown in Fig. 1 in the spring locked position, and in Fig. 2 in the locked position without springs.

Referring now to the drawings: 30 is the brickwork constituting the coke oven structure and is one end of the coking chambers 2 of a coke oven battery. 28 is the metal covering mounted on an insulating layer 29 covering the brickwork 30 on either side of the mouth of the coking chamber 2. 31 is one of the buckstays of the coke oven battery.

15 The mouth of each end of the coking chambers is surrounded by a cast metal door frame 8 of L-shaped cross section held against the ends of the brickwork 30 in any suitable manner, not shown. The refractory plug portion 1 of the oven door projects into the coke oven chamber 2 and is supported by a cast iron door-back frame 3. The 20 door back frame 3 is connected with a door plate 4 which is provided with a door flange 5 extending all around the door plate. The sealing frame 6 which is connected with the door plate 4 seals with its flanged end 7, in the locked position of the door, against the sealing surface of the 25 door frame 8. On the door frame 8 latch hooks 9 are arranged behind which the arm means of the double arm latch bar 10 grasps when the door is in locked position.

30 Screw bolts 32 mounted in angular brackets 33 fixed on the flange 5 of the door plate 4 serve for pressing the edge 35 portion 17 of frame 6 against the sealing surface of the door frame 8.

35 A preferred embodiment of the invention comprises an axially movable latch bolt member in which a latch bolt 12 is screwed at its rear portion into a mounting 11 which is connected with the door plate 4. The rear portion of the bolt is secured against twisting or turning, as by means of a key. The front end portion 13 of the latch bolt 12 is also screw threaded and provided with an axially movable part in the form of a nut portion 14 which is 40 axially adjustably arranged on the thread of the front end 13 of the latch bolt and provided with an abutment member in the form of a collar 15. The front end 16 of the nut portion 14 projects beyond the latch bar hub 17 of the latch bar 10 and is made polygonal so that the adjustable nut portion 14 may be turned by means of a hand wrench, or a corresponding coupling member of a mechanical device for operating the latch.

45 The latch bar hub 17 is provided at the one end with a cooperating abutment in the form of a collar 18 which in 50 Fig. 1 is directed by collar 15 toward the oven chamber. The latch bar arm means 10 rests therefore through its latch bar hub 17, by means of a ball bearing 19, on the movable part in the form of the adjustable nut portion 14 of the latch bolt 12 in such a manner that when turning 55 the adjustable nut portion 14 of the latch bolt for the axial inward movement a corresponding pressure is exerted through ball bearing 19 against the abutment collar 18, of the latch bar hub 17 to release the latch bar hub from the pressure urging it towards the latch hooks 9 and the latch bar 10 is thereby moved from its rest against the latch hooks 9. The abutment collar 18, of the latch bar hub 17 thereby presses against a pressure plate 20 which

is rigidly connected by fastening means, studs 21, with the latch bar hub 17. Thereby a spring assembly is compressed formed of lock spring washers 22. As is apparent from Fig. 1 the remaining inner portion of the latch bar hub 17 is substantially made cylindrical so that should the adjustable nut portion 14 be turned sufficiently far back axially outward in the opposite direction in locking the door, the collar 18 no longer exerts pressure against the pressure plate and spring 22, but rather the spring exerts pressure on the collar to spring latch the door 10 against latch hook 9 through latch bar 10.

The spring washers 22 are accommodated in a housing 23 the bottom of which is connected by studs 25 with the mounting 11. The pressure plate 20 also constitutes a restraining means and is provided with key arms 26 which engage into openings or receptacles in the housing 23 so that the pressure plate 20 and the latch bar hub 17 connected thereto cannot be rotated when latch bar 10 is swung on hub 17 as a pivot.

For loosening the locked door the head 16 of the movable part in the form of the axially adjustable nut portion 14 of the latch bolt 12 is engaged and turned so that the spring washers 22 are somewhat compressed and the latch bar 10 moved from resting against the latch hooks 9. Now the latch bar 10 is swung out of the reach of the hooks 9. The thread between the latch bar hub 17 and latch bar arm means 10 is so constructed that when the latch bar arm means is swung it is moved away somewhat from the oven in a direction outwardly along the oven axis. In this manner it is possible to easily swing the latch bar 10 in unlatching the door, if the same should come to rest or jam against the flange 5 which extends all around the door plate when compressing spring 23.

When returning the door to the oven mouth the spring washers 22 of the door are held compressed by the mechanical device for operating the latch, which device is mounted on the conventional door lifting device and the springs 22 have the same extent of compression as in loosening the locked door. The latch bar arm means 10 can therefore readily be swung again into its closing position with latch hooks 9.

In order to be able to remove the lock spring washers 22 in case of failure of any members of the pack of spring washers 22 or a deficiency of replacements or for any other reason, the axially adjustable nut portion 14 of the rotary screw, latch bolt 12 is first screwed off the rear portion of the bolt and the pressure plate 20 loosened by unscrewing the studs 21 from the latch bar hub 17 after having taken off the latch bar 10 and removed the spring washers 22. Then the latch bar 10 is turned around so that the abutment collar 18, will come into the reverse position as illustrated by 18a in Fig. 2. The pressure plate 20 can now be again connected with the latch bar hub 17 by means of the fastening means, in the form of studs 21 and the threading 27 which is also provided on the other side of the latch bar hub. In this position also the key arms 26 engage again into the openings of the receptacles of the housing 23 so that the latch bar hub 17 again cannot be rotated.

In this way, such a position of the latch bar 10 and of its hub 17 screwed therein will be taken as is illustrated in Fig. 2. In this position the abutment member, collar 15, of the axially movable part, the adjustable nut portion 14 of the latch bolt exerts a pressure on the abutment, as the collar at 18a, of the latch bar hub 17 by means of the ball bearing 19, as at 19a, upon turning the adjustable nut portion 14 outwardly. By turning the adjustable nut portion 14 in that direction, which will cause an axial movement of the latch bar 10 together with its hub 17 away from the oven chamber 2, a pressure of the oven door 4 together with its sealing frame 7 is exerted on the sealing surface of the door frame 8.

What we claim is:

1. A door locking device for doors of coking chambers 75

of horizontal coke ovens comprising an axially movable latch bolt member, a latch bar hub mounted on said bolt member, and a lock spring cooperating with said hub whereby the door is kept close to the door frame of the oven chamber by pressure of said spring between the door and said hub in locking position of the door and hub, characterized by a reversible latch bar hub that is reversibly mountable on said axially movable latch bolt member, an abutment member on the axially movable latch bolt member and a cooperating abutment on the latch bar hub which coact, in one position of the latch bar hub, to transmit force to the spring to compress the same to release the latch bar hub to unlocking position relative to the door, upon axial movement of the axially movable latch bolt member in one direction, and which coact in the reversed position of the latch bar hub on the axially movable latch bolt member to transmit force of the latter to the latch bar hub to lock the same with omission of the lock action of the lock spring, upon axial movement of the axially movable latch bolt member in the opposite direction to the direction it moves to compress said lock spring.

2. A door locking device as claimed in claim 1, and in which the axially movable latch bolt member comprises a rotary bolt with screw threads thereon for effecting its axial movement on rotation of the bolt, and in which the latch bar hub is mounted on the rotary bolt for axial movement of the rotary bolt relative to the latch bar hub, and in which the abutment and the abutment member comprise a collar on the latch bar hub and a cooperating collar on the rotary bolt.

3. A door locking device as claimed in claim 2, and in which the rotary bolt also comprises a pin with screw threads at the rear portion thereof for attachment to the door and a key for restraining the pin from rotation, screw threads on the front portion of the pin, a movable part in the form of a nut threaded on the screw threads on the front portion of the pin for axial movement therewith, and in which the latch bar hub is freely rotatably mounted on the nut, and in which the abutment member in the form of said cooperating collar is on the nut.

4. Apparatus as claimed in claim 2, and which includes restraining means for securing the latch bar hub against rotation upon rotary screw rotation of the axially movable latch bolt, and which includes latch bar arm means rotatably carried on the latch bar hub.

5. Apparatus as claimed in claim 4, characterized by a threaded connection between the latch bar arm means and the latch bar hub by which the arm means is moved away from the door upon rotation of the latch bar arm means on the latch bar hub during rotation of the arm means out of contact with latch hooks therefor in unlatching the locking device.

6. Apparatus as claimed in claim 4, and in which the restraining means for securing the latch bar hub against rotation comprises a pressure plate which is arranged between the latch bar hub and the lock spring and fixedly connected to the latch bar hub, and in which the pressure plate is secured against rotation by means of key arms on the plate which are removably insertable in receptacles therefor in a housing enclosing the lock spring.

7. Apparatus as claimed in claim 6, characterized by fastening means on both axial sides of the latch bar hub for fixedly connecting the pressure plate thereon whereby the pressure plate with its key arms can be used on the latch bar hub in both the normal and the reversed position of the latch bar hub on the axially movable rotary latch bolt.
